C. B. MICHEL

FAUCET

Filed Sept. 22, 1923

Inventor
CLARENCE B. MICHEL

By *John Johnson*

Attorney

UNITED STATES PATENT OFFICE.

CLARENCE B. MICHEL, OF ST. PAUL, MINNESOTA.

FAUCET.

Application filed September 22, 1923. Serial No. 664,226.

To all whom it may concern:

Be it known that I, CLARENCE B. MICHEL, a citizen of the United States, residing at St. Paul, in the county of Ramsey and State of Minnesota, have invented certain new and useful Improvements in Faucets, of which the following is a specification.

My invention relates to improvements in faucets, and has for its object to provide a faucet adaptable for use as an ordinary discharge faucet, a drinking fountain, and a sprayer for use as in spraying a stream upon dishes, vegetables, etc., for cleansing purposes.

My invention consists particularly in the improved features of construction and combination whereby the three characters of water discharging, i. e., the ordinary full discharging, the spraying, and the drinking fountain discharge may be regulated with the minimum number of parts and simplicity of construction and with a maximum of efficiency, and to this end consists in the features of construction and combination hereinafter particularly described and claimed.

In the accompanying drawings:

Figure 1 is a perspective view of a hot and cold fitting, equipped with my improved combination spout.

Figure 2 is a vertical section lengthwise of the spout with the parts in position to form a drinking fountain.

Figure 3 is a fragmentary view of the outlet end of the spout.

Figure 4 is a vertical section lengthwise of the spout with the parts in position for ordinary full water discharge.

Figure 5 is a fragmentary perspective view of the spout.

Figure 6 is a side view of the port end of the spout; and

Figure 7 is a sectional view on line 7—7 of Figure 2.

In the drawings, 1 designates a combination hot and cold water fitting, the faucet handles 2 and 3 being connected by the conduit 4. The conduit is formed with a downwardly extending discharge branch 5, having a discharge opening 6. The discharge branch is exteriorly threaded at 7 to be screwed into the interior threaded upper end of the connecting sleeve 8, the latter being formed with a shoulder 9 opposed to the end of the branch 5.

Swiveled in the sleeve 8 is the upwardly

extending portion 10 of the body 11 of my improved combination faucet, said upwardly extending portion 10 being formed at its upper end with an outwardly extending shoulder 12, between which and the shoulder 9 is adapted to be interposed a packing 13. The body 11 is in the form of a right-angled elbow, formed with a vertical bore 14 and a connecting bore 15 extending at right angles to the vertical bore. The bore 15 is inwardly tapered to receive the tapered inner end of the spout 16. The spout 16 is held within the elbow 11 by means of a collar 17 threaded over the horizontally projecting end of the elbow and fitting over the spout.

The spout, inside of the collar 17, is formed with a circumferential flange 18, between which flange and the collar 17 is positioned the packing ring 19 and the slideable gland ring 20 surrounding the spout. Thus, by tightening the collar 17, pressure is obtained against the flange 18 of the spout through the intermediate packing and gland rings to hold the spout in position and maintain a water tight joint.

The spout is tubular for its length and formed with a closed inner end, the spout being formed adjacent to the closed inner end with a port opening 21 and with a surrounding annular port 22 in alignment with the port 21 and of relatively small area.

The outer end of the spout is formed with a laterally directed nozzle 23, having a central discharge opening 24 connected with the interior opening 25 extending lengthwise of the spout.

The nozzle is also formed with an annular opening 26 surrounding the discharge opening 24, the opening 26 being connected on one side by a port 27 with the opening 25 within the spout. The inner wall 28, forming the central discharge opening of the nozzle, is at its outer end connected with the outer wall of the nozzle by the perforated wall 29, which constitutes a perforated discharge for the annular opening 26.

Fitted within the outer end of the spout is a rotary controlling valve 30, closed at its outer end and having a central passageway 31. The valve is held in position in the nozzle by the screw threaded cap 32, having interior threaded engagement in the end of the nozzle. The valve is adapted to be rotated by the handle 33 secured upon its outer end and the rotation of the valve is limited

by a stop 34, secured in the wall of the nozzle and fitting into a slotted opening 35 in the inner end of the valve. The valve 30 is normally held pressed outward by a coil 5 spring 39, seated behind the valve. The pressure of the coil spring thus tends to hold the valve in adjusted positions.

The valve is formed in its side wall with a pair of openings 36 and 37, in alinement, 10 respectively, with the discharge opening 24 and the port 27, the openings 36 and 37 being circumferentially spaced apart so that the valve may be turned to bring either desired port into register with either discharge 15 opening. The valve is also preferably formed with an opening 38 to register with the discharge opening 24 when the opening 37 is in registration with the discharge port 27.

20 My construction is designed especially for three purposes:

The permitting of a maximum discharge of water through the nozzle with the parts in the position shown in Figure 4; the producing 25 of a spraying stream, with the nozzle in the position shown in Figure 4, and the controlling valve suitably adjusted; and the furnishing of a restricted fountain stream for drinking purposes, with the parts in the 30 position shown in Figure 2.

In operation, with the parts in the position shown in Figure 4, the water will pass in an unrestrained manner into and through the nozzle and through the controlling valve 35 and out through the port opening 36 of the valve and discharge opening 24 of the nozzle. By turning the handle 33, with the parts in the position shown in Figure 4, to carry the port 36 out of registering position with 40 the discharge opening 24 and bring the port opening 37 into registering position with the port 27, and opening 38 into registration with the discharge opening 24, the water is discharged through the perforated wall 45 29 to constitute a cleansing stream, with a small stream passing through the discharge opening 24, for use in dishwashing, vegetable washing, and similar operations. With the parts in the position shown in Figure 4, 50 the full stream of water passes from the main faucet conduit 6, through the port opening 21 into the spout. With the parts in the position shown in Figure 2, the passage of water into the spout is restrained 55 or reduced by being compelled to pass through the smaller annular port 22 extending around the spout in alinement with the port 21, and thus a restrained stream passes to the spout to serve as a drinking 60 fountain. When the parts are in the position shown in Figure 2 to constitute a drinking fountain or nozzle, with the restrained stream of water passing upwardly through the discharge opening 24, the water rising 65 above the top of the nozzle will drop back

upon the wall 29 to facilitate drinking from the stream.

I claim:

1. In a combined faucet and drinking fountain, a spout rotatably connected to a supply pipe and having an opening in a side thereof with a channeled groove extending around the periphery of the pipe at the point of said opening, an offset portion at the end of the spout having a central opening, a chamber surrounding the central opening, having a plurality of perforations therein, and a hollow cylinder rotatably mounted in the spout adjacent the offset portion, said hollow cylinder having a pair of perforations in a side thereof, one of said openings being positioned to register with the central opening in the offset portion of the spout, the other of said openings being positioned to register with an opening in the perforated chamber surrounding the central opening, to cause a fluid passing through the device to be discharged through the central opening or through the perforated chamber, as desired. 90

2. The combination with a water supply pipe and a spout rotatably mounted in connection therewith, said spout being formed with a relatively large and a relatively small port adapted, in the rotation of said spout, to separately establish communication between the water supply pipe and spout; of a laterally directed nozzle carried by the outer end of said spout, said nozzle being formed with a central discharge opening and a surrounding discharge opening, said second discharge opening being formed with a perforated discharge end, a rotary hollow valve mounted in the end of said spout, said valve being formed with a relatively large port opening and a circumferentially spaced smaller opening, said valve being rotatable to bring said larger opening into registering position with the central discharge opening of the spout, or said smaller discharge opening into registering position with the surrounding discharge opening of the spout with the opposed opening closed. 105

3. The combination with a water supply pipe and a spout rotatably mounted in connection therewith, said spout being formed with a relatively large and a relatively small port, adapted, in the rotation of said spout, to separately establish communication between the water supply pipe and spout; of a laterally directed nozzle carried by the outer end of said spout, said nozzle being formed with a central discharge opening and a surrounding discharge opening, said second discharge opening being formed with a perforated discharge end, a rotary hollow valve mounted in the end of said spout, said valve being formed with a relatively large port opening and a circumferentially spaced smaller 110

opening, said valve being rotatable to bring said larger opening into registering position with the central discharge opening of the spout, or said smaller opening into registering position with the surrounding discharge opening of the spout, with the opposed opening closed, and a stop carried by said spout projecting inwardly into a circumferentially slotted opening in said valve 10 to limit the rotary movement of said valve.

4. The combination with a water supply pipe and a spout rotatably mounted in connection therewith, said spout being formed with a relatively large and a relatively small 15 port adapted, in the rotation of said spout, to separately establish communication between the water supply pipe and spout; of a laterally directed nozzle carried by the outer end of said spout, said nozzle being 20 formed with a central discharge opening

and a surrounding discharge opening, said second discharge opening being formed with a perforated discharge end, a rotary hollow valve mounted in the end of said spout, said valve being formed with a relatively large 25 port opening and a circumferentially spaced smaller opening, said valve being rotatable to bring said larger opening into registering position with the central discharge opening of the spout, or said smaller discharge 30 opening into registering position with the surrounding discharge opening of the spout, with the opposed opening closed, and a screw threaded cap mounted upon the outer end of said valve and having interior 35 threaded connection with said spout and an exterior controlling handle for said valve.

In testimony whereof I affix my signature.

CLARENCE B. MICHEL.
